UNITED STATES PATENT OFFICE.

LAWRENCE R. QUINN, OF NEWARK, NEW YORK, ASSIGNOR TO REED MANUFACTURING COMPANY, OF NEWARK, NEW YORK, A CORPORATION OF NEW YORK.

COVER FASTENER OR CLAMP.

1,111,272.

Specification of Letters Patent. Patented Sept. 22, 1914.

Application filed April 28, 1914. Serial No. 835,056.

To all whom it may concern:

Be it known that I, LAWRENCE R. QUINN, a citizen of the United States, and resident of Newark, in the county of Wayne and State of New York, have invented certain new and useful Improvements in Cover Fasteners or Clamps, of which the following is a specification.

This invention relates to means, in the nature of a clamp, whereby a cross-bar, cover, or the like may be conveniently and firmly secured to the top of a pail or other receptacle.

The invention, although obviously applicable to a variety of uses, is particularly useful in connection with a device, such as a bread-mixer, in which moving parts are carried by a cross-bar secured to the top of a sheet-metal pail or receptacle of ordinary form.

The object of the invention is to produce a clamp, for the purpose in question, which may be conveniently and quickly thrown into or out of operative position, which will hold the cross-bar securely when in use, and which is inexpensive in construction and compact in form.

To the foregoing ends I employ a clamp in which a movable member is pivotally mounted upon the end of the cross-bar or upon a suitable projection therefrom, in such a position that the clamping-member may be swung into and out of position beneath an outwardly-projecting ledge at the upper edge of the vessel, this ledge being, preferably, the ordinary wired edge, such as is commonly employed in sheet-metal vessels.

Other features of the invention will be more particularly described hereinafter.

In the accompanying drawings:—Figure 1 is a perspective view of a portion of a sheet-metal vessel and a cross-bar provided with a clamp embodying the present invention, showing the parts in inoperative position; and Fig. 2 is a vertical sectional view of the same parts, showing them in operative position.

The invention is illustrated as applied to a bread-mixer or similar device, in which a sheet-metal receptacle or pail 5 carries a cross-bar 6 of heavy sheet-metal. The pail is provided with a wired upper edge 7, which provides an outwardly-projecting abutment or ledge adapted to coöperate with

the clamping-member. The end of the cross-bar 6 is bifurcated, forming arms 8 which extend downwardly and outwardly and are provided, at their outer ends, with a pivot-pin 9 fixed in sleeves formed of the sheet-metal of the arms. This pin 9 constitutes a pivotal bearing for the clamping-member, which is arranged to turn upon it between the arms 8. The clamping-member comprises a single strip of sheet-metal bent to form a lever 10 and a cam-like detent-member 11. This detent-member is of such shape that when the lever 10 is swung inwardly, to the position of Fig. 2, the detent-member is brought into a position beneath the ledge 7, so as to lock the cross-bar against vertical movement. Preferably the detent is of such dimensions that it will have a wedging action against the ledge, and when in its final position the pressure of the detent against the ledge will be somewhat relieved, owing to the curved form of the detent, so that the detent tends, by reason of the resiliency of the sheet-metal, to remain in operative position. When the clamp is to be released, however, it is necessary only to pull the lever 10 upwardly and outwardly, whereupon the detent is forced out of engagement with the ledge and swing into the inoperative position shown in Fig. 1. With the parts in this position the cross-bar may be raised from the pail.

To insure the placing of the cross-bar in proper diametral position upon the pail, and also to secure the cross-bar against lateral movement in case the frictional engagement of the parts is not sufficient for this purpose, the pail is preferably provided on its outer surface, a short distance beneath the ledge 7, with a bail-shaped metal member 12 which receives the hook-like extremity of the detent 11 when the latter is in operative position, as shown in Fig. 2.

It will be apparent that the form and structure of the parts of the above-described clamp, particularly the formation of the clamping-member of a single piece of sheet-metal bent to provide a lever, a pivot-embracing portion, and a detent-member, are such as to permit the device to be cheaply manufactured, and it will be apparent from Fig. 2 of the drawings that the parts, when in operative position, provide a compact device free from inconvenient projections.

I claim:

1. The combination, with a vessel having an outwardly-projecting ledge at its upper edge, and a cross-bar adapted to be supported on the top of the vessel, of a pivotal bearing-member rigidly connected with and supported by, the cross-bar in a position outside of and below said ledge on the vessel; and a clamping-member pivoted on said bearing-member, and comprising a cam-like detent adapted to swing into and out of position beneath said ledge, and a lever rigidly connected with the detent.
2. The combination, with a vessel having an outwardly-projecting ledge at its upper edge, and a cross-bar adapted to be supported on the top of the vessel, of a pivotal bearing-member rigidly connected with, and supported by, the cross-bar in a position outside of and below said ledge on the vessel; and a clamping-member pivoted on said bearing-member, and comprising a cam-like detent adapted to swing into and out of position beneath said ledge, and a lever rigidly connected with the detent, the lever being adapted to lie above and close to the cross-bar when the detent is in operative position.
3. The combination, with a vessel having an outwardly-projecting ledge at its upper edge, and a cross-bar adapted to be supported on the top of the vessel, of a pivotal bearing-member supported by the cross-bar in a position outside of and below said ledge on the vessel; and a clamping-member pivoted on said bearing-member and comprising a single strip of sheet-metal bent to form, at one end, a lever for manual operation, at an intermediate point, a sleeve to embrace the bearing-member, and at the other end, a detent with a convex cylindri-

cal surface adapted to coöperate with the lower surface of said ledge.

4. The combination, with a vessel having an outwardly-projecting ledge at its upper edge, and a cross-bar adapted to be supported on top of the vessel, of a pivotal bearing-member supported by the cross-bar in a position outside of and below said ledge on the vessel; a clamping-member pivoted on said bearing-member, and comprising a detent adapted to swing into and out of position beneath said ledge, and a lever for manual operation of the clamping-member; and means, fixed to the vessel beneath said ledge, for engaging the detent laterally to prevent lateral displacement of the cross-bar.

5. The combination, with a vessel having an outwardly-projecting ledge at its upper edge, and a cross-bar adapted to be supported on the top of the vessel, of arms projecting outwardly and downwardly from the end of the cross-bar; a pivot-pin supported by said arms in a position outside of and below said ledge of the vessel; a clamping-member mounted on the pivot-pin, and comprising a detent, hook-shape in cross-section and adapted to swing into and out of position beneath said ledge, and a lever for manual operation of the clamping-member; and a bail-shaped member fixed to the vessel beneath said ledge and adapted to receive the hook-shaped detent when the latter is in operative position.

In testimony whereof, I affix my signature in presence of two witnesses.

LAWRENCE R. QUINN.
